[57] CLAIM

The ornamental design for a molded fisherman's box with
access opening, as shown.

DESCRIPTION

FIG. 1 is a perspective view of the molded fisherman's box
with access opening showing our new design;

FIG. 2 is a left side elevational view thereof;

FIG. 3 is a front elevational view thereof;

FIG. 4 is a rear elevational view thereof;

FIG. 5 is a right side elevational view thereof;

FIG. 6 is a top plan view thereof;

FIG. 7 is a bottom plan view thereof; and,

FIG. 8 is a perspective view of a second embodiment, with
all other views being the same as shown in the first embodiment
with the exception of the surface material.

1 Claim, 4 Drawing Sheets
